PLUCKER FINGER FOR CHICKEN PLUCKING MACHINE

Benjamin Levin, 511 Commercial St., Glendale, Calif.

Filed Jan. 26, 1962, Ser. No. 68,535

Term of patent 14 years

(Cl. D11—1)

FIG. 1

FIG. 6

FIG. 2

FIG. 3

FIG. 4

FIG. 5

FIG. 7

FIGURE 1 is a perspective view of a plucker finger for chicken plucking machine showing my new design; FIGURE 2 is a side elevational view thereof; FIGURE 3 is a bottom view thereof; FIGURE 4 is a front elevational view thereof; FIGURE 5 is a rear elevational view thereof; FIGURE 6 is a cross sectional view taken on line 6—6 of FIG. 2; and FIGURE 7 is a cross sectional view taken on line 7—7 of FIG. 2.

I claim:
The ornamental design for a plucker finger for chicken plucking machine, substantially as shown.
